COVER DISH.

No. 22,621.

Patented July 18, 1893.

UNITED STATES PATENT OFFICE.

CHARLES EDWARD HAVILAND, OF LIMOGES, FRANCE.

DESIGN FOR A COVER-DISH.

SPECIFICATION forming part of Design No. 22,621, dated July 18, 1893.

Application filed June 22, 1893. Serial No. 478,514. Term of patent 14 years.

To all whom it may concern:

Be it known that I, CHARLES EDWARD HAVILAND, a citizen of the United States, residing at the city of Limoges, in the Republic of France, have invented and produced a new and original Design for a Cover-Dish and other Articles, of which the following is a specification, reference being had to the accompanying drawings, forming part thereof, and in

which—

Figure 1 is a side elevation of a cover-dish embodying my design. Fig. 2 is a top view of same, and Fig. 3 is a vertical section of a portion of same on the dotted line 3—3 of Fig. 2.

The leading features of my design consist of the ornamental form and configuration of the dish, substantially as illustrated in the accompanying drawings.

The sides of the dish are composed of the scalloped sections A, which curve gracefully downward and outward and thence on a well rounded curve extend inward on ornate lines to the base B, which is ornamented along its

edge by the scalloped line of beading C and, 25 at intervals, the ornate surfaces D inclosed at opposite sides by said beading. At opposite sides of the body of the dish are the ornamental scroll handles E. The cover F has along its scalloped edges the ornamentation 30 composed of the line of scalloped beading G drawn inward at intervals, as shown at H, and outlining at such points spaces for the ornate surfaces I. The central field of the cover F is occupied by the ornamental scalloped 35 raised portion J bearing the ornamental scroll handle K.

What I claim is—

The design for a cover-dish and other articles substantially as shown and described. 40

Signed at the city of New York, in the county and State of New York, this 20th day of June, A. D. 1893.

CHARLES EDWARD HAVILAND.
